UNITED STATES PATENT OFFICE.

JOHN E. SPONSELLER, OF HOISINGTON, KANSAS.

BAND-CUTTER AND FEEDER FOR THRESHING-MACHINES.

SPECIFICATION forming part of Letters Patent No. 759,322, dated May 10, 1904.

Application filed June 30, 1903. Serial No. 163,766. (No model.)

To all whom it may concern:

Be it known that I, JOHN E. SPONSELLER, a citizen of the United States, residing at Hoisington, in the county of Barton and State of 5 Kansas, have invented a new and useful Band-Cutter and Feeder for Threshing-Machines, of which the following is a specification.

This invention relates to band-cutters and feeders for threshing-machines; and it has for 10 its object to provide a device of this class which shall be capable of being easily and conveniently adjusted according to the condition of the grain that is being fed, so as to feed the same at any desired rate of speed, 15 such adjustment being accomplished in an extremely simple and convenient manner and without the use of automatic governing devices, which latter in a device of this kind are extremely liable to become obstructed, and 20 consequently inoperative.

My improved adjusting device is so disposed and arranged as to be capable of being operated while the machine is running, this being an important feature, for the reason 25 that the condition of the grain is not always uniform.

My improved feeding device is adapted to feed either bound or unbound grain, it being provided with band-cutting knives which will 30 sever the bands when sheaves are fed to the machine.

My invention consists in certain improvements in the construction, arrangement, and combination of the constituent parts, which 35 will be hereinafter more fully described.

In the drawings hereto annexed I have shown one form of embodiment of my invention which is simple and effective; but I desire to have it understood that I do not limit 40 myself with regard to the structural details herein shown, but reserve the right to such changes as to size, proportion, and general manner of assemblage of the parts of the device as are within the spirit and scope of my 45 invention.

In said drawings, Figure 1 is a perspective view of a band-cutter and feeder constructed in accordance with the principles of my invention, the feeding device being shown as 50 set to its greatest capacity. Fig. 2 is a lon-

gitudinal section. Fig. 3 is a transverse sectional view taken on the line 3 3 in Fig. 2. Fig. 4 is a cross-sectional view, enlarged, of the shaft 13, tubular sleeve 15, and related parts.

Corresponding parts in the several figures are indicated by similar numerals of reference.

A frame (generally designated 1) is provided with bearings for a crank-shaft 2, which in the example shown in the drawings has 60 been illustrated as being provided with four separate cranks 2^a, which are set at different angles. The crank-shaft 2 has been shown as journaled in boxes or bearings 3, attached to uprights 4 of said frame. These uprights are 65 provided with brackets 5 and 6, which converge forwardly and which are connected at their front ends by means of massive castings 7, having segmental slots 8. The castings 7 are connected by a cross-brace 9, and the up- 70 uprights 1 of the frame are likewise connected by a cross-brace 10, said braces serving to hold the parts connected in their proper relative position, and thereby prevent unnecessary vibration when the device is in operation. 75

The castings 7 are provided on their inner sides adjacent to the segmental slots 8 with segment-racks 11, which are engaged by pinions 12 upon a shaft 13, the ends of which extend through the segmental slots, one or both 80 of said ends being provided with handles 14. The shaft 13 carries between the segment-racks a tubular sleeve 15, upon which are mounted a plurality of blocks 16, which are capable of rocking independently upon the sleeve 15, 85 while the latter in like manner is capable of oscillating upon the shaft 13. It will be observed that by turning the latter by means of the handle 14 the pinions at the ends of the shaft will engage the segment-racks, thus 90 causing the shaft 13, with its related parts, to move in an upward or downward direction in the segmental slots, according to the direction of rotation. Any suitable means may be provided for securing the shaft at any desired 95 point of adjustment. This may, if desired, be accomplished by simply tightening the nuts 17, which hold the handles upon the ends of the shaft 13. It will be observed that by thus tightening the nuts upon the shaft 13 the 100

- segmentally-slotted brackets will be clamped between said nuts and the pinions 12. The inward strain thus exercised upon said pinions will, however, be prevented from causing the 5 dislodgment of said pinions, owing to the interposition between them and the tubular shaft or sleeve 15, as will be readily understood. Consequently no matter to what extent the nuts 17 are tightened the tubular 10 sleeve 15 will cause the brackets to remain properly spaced, and the blocks 16, journaled upon sleeve 15, will thus at all times be capable of rocking freely with relation to each other.
- 15 The blocks 16, which are journaled upon the sleeve 15, are each provided with a pair of downwardly-extending fenders 18, which are connected pivotally near their lower ends with the front ends of the feed-bars 19, which are 20 provided with band-cutting knives 19^a and the rear ends of which are connected by means of boxes 20 with the cranks 2^a upon the crank-shaft 2, it being obvious that an equal number of cranks 2^a and swinging blocks 16 have been 25 provided. The boxes 20, by means of which the feed-bars 19 are connected with the cranks, are preferably secured upon the upper sides of said feed-bars. The under sides of the latter carry at their front ends and directly under 30 the cranks the feeders 22, which serve to convey the material fed to the cylinder. Owing to this construction the feeders only will engage the material that is to be fed to the cylinder, while the boxes or bearings upon which 35 said feeders are mounted are disposed upon the upper sides of the feed-bars, and consequently out of the way, thereby avoiding the liability of clogging the feeding mechanism at this important point.
- 40 The braces 6 of the frame are provided with boxings or bearings in which is journaled a transverse shaft 23, which constitutes the operating-shaft of an endless carrier 24, which is mounted in a trough or casing 25 of ordinary construction, which is detachably connected with said shaft, so that when not in use it may be conveniently removed for transportation or storage. The outer end of the carrier-casing, which may be supported in any 45 suitable manner, is provided with a shaft 26 to support the outer end of the endless carrier. The latter is constructed in the ordinary manner of chains 27, engaging sprocket-wheels 28 and 29 upon the shafts 23 and 26 and connected 50 at intervals by slats 30, engaging the bottom 31 of the carrier-trough.
- 55 The crank-shaft 2 has a band-wheel 32, from which a belt 33 extends to the source of power. This belt normally runs slack when it is not 60 desired to operate the feeding device. When it is desired to throw the latter into active operation, this may be accomplished by means of a tightening-pulley 34, mounted upon a lever 35, which is suitably fulcrumed upon the frame 65 of the device and the handle end of which en-

gages a rack 36, whereby it may be held in adjusted position.

The crank-shaft 2 carries adjacent to the band-wheel 32 a pinion 37, which meshes with a spur-wheel 38, which is journaled upon a stub 70 attached to the frame and which also carries a sprocket-wheel 39, connected by a chain 40 with a sprocket-wheel 41 upon the shaft 23 of the endless carrier, which is thus driven when the machine is in operation. 75

42 designates a feed-plate which is hingedly connected at its inner end with the frame of the machine, said inner end being extended under the delivery end of the endless carrier. This frame is adapted to extend over the feed-table 80 of the machine to which the device is applied, so that the material passing from the endless carrier will be carried by the feeder 20 over said feed-plate and between the cylinder and concave of the machine. This plate 42 is not 85 only detachable, in order that it may be removed when necessary to afford access to the operating parts of the device, but it is my intention to provide means whereby its rear or delivery end may be vibrated, thus serving to 90 agitate the material that is being delivered to the threshing mechanism, the advantage of which is obvious, inasmuch as lumps or knots which may exist in the grain, especially when the latter is damp and tangled, will have an 95 opportunity of being disentangled before passing to the threshing mechanism. This vibration or agitation of the feed-plate may be accomplished in numerous well-known ways.

From the foregoing description, taken in 100 connection with the drawings hereto annexed, the operation and advantages of my invention will be well understood. When the crank-shaft 2 is in operation, motion is transmitted to the endless carrier 24 and likewise to the 105 feed-bars 19, which in turn serve to vibrate the fenders 18, depending from the oscillating blocks 16. These fenders have been previously set to any desired elevation according to the condition of the grain that is to be operated upon, thereby positively limiting the amount of grain fed to the machine. By manipulating the handles 14 of the shaft traveling in the segmental slots 8 the said fenders, together with the front ends of the feed-bars, 110 may be elevated so as to permit any desired quantity of grain to pass to the machine. It is obvious that the fenders also operate as feeders, which by positively engaging the grain will force it under the feed-bars, which latter are provided with band-cutting knives 115 19^a, which latter in addition to cutting the bands naturally assist in feeding the grain. 120

The entire device is simple, easily operated, and very effective for the purposes for which it is intended. 125

Having thus described my invention, I claim—

1. In a band-cutter and feeder, a crank-shaft, a vertically-adjustable shaft, a sleeve 130

upon the latter, oscillatory blocks mounted upon said sleeve, fenders depending from said blocks, and feed-bars having boxes journaled upon the cranks of the crank-shaft and connected pivotally at the opposite ends with the fenders, near the lower ends of the latter.

2. In a band-cutter and feeder, a frame having forwardly-extending converging brackets, castings connecting the converging ends of said brackets and provided with segmental slots and segmental rack-bars adjacent to the same, a shaft mounted adjustably in said slots and having pinions engaging the segment-racks, means for rotating the said shaft to

effect the vertical adjustment thereof, a sleeve 15 mounted upon said shaft between the pinions thereof, blocks independently oscillatory upon said sleeve, fenders depending from said blocks, a driven crank-shaft, and feed-bars connecting the latter with the fenders and provided with band-cutting knives.

In testimony that I claim the foregoing as my own I have hereto affixed my signature in the presence of two witnesses.

JOHN E. SPONSELLER.
